UNITED STATES PATENT OFFICE.

WILLIAM R. CLARK, OF DETROIT, MICHIGAN, ASSIGNOR TO THE SINGER
MANUFACTURING COMPANY, OF NEW JERSEY.

COMBINED HEMMER AND LACE-GUIDE FOR SEWING-MACHINES.

SPECIFICATION forming part of Letters Patent No. 332,700, dated December 22, 1885.
Application filed July 7, 1885. Serial No. 170,884. (Model.)

To all whom it may concern:

Be it known that I, WILLIAM R. CLARK, a citizen of the United States, residing at Detroit, in the county of Wayne and State of Michigan, have invented certain new and useful Improvements in Combined Hemmer and Lace-Guide for Sewing-Machines, of which the following is a specification, reference being had therein to the accompanying drawings.

10 The object of my invention is to provide a simple and convenient attachment for sewing-machines, for turning a hem on the edge of a piece of fabric as the latter passes to the sewing mechanism, and simultaneously guiding a strip of lace or other material to the needle.

15 To this end my device consists of a supporting-plate, preferably provided with a presser-foot, and thus adapted for attachment to the presser-bar of a sewing-machine, said plate

20 having on its upper side a hemmer of any ordinary or suitable construction. In front of the hemmer is preferably placed a friction-spring, between the free end of which and an inclined rib or projection beneath it the fabric 25 to be hemmed passes, said inclined projection, against which the fabric is gently pressed by said spring, having a tendency to deflect the fabric toward the hemmer in a well-known manner, and thus keep the edge of the goods 30 in the hemmer. The supporting-plate is provided on its under side with a guiding-passage for a strip of lace or other material, said passage being mainly on the inner side or to the right of the hemmer, the outer edge of said 35 passage being directly beneath or in line with the hemmer, so that the edge of the strip guided thereby will be presented to the needle beneath the hem, and will thus be attached to the fabric by the line of stitches by which the 40 turned hem is secured. The strip-guiding passage is preferably made adjustable to adapt it for use with strips of different widths.

In the drawings, Figure 1 is a plan view of my combined hemmer and guide. Fig. 2 is a bottom view, Fig. 3 a side view, and Fig. 4 a front view, of the same. Fig. 5 is a perspective bottom view of my device with the guide-piece detached, and Fig. 6 is a perspective view of said guide-piece.

50 A indicates the main or supporting plate of

my device, and B is a presser-foot, by which said plate may be removably fastened to the sewing-machine presser-bar. Secured to the plate A in front of the needle-opening b of the presser-foot is an ordinary twisted hemmer, C, 55 said hemmer being preferably formed integral with its attaching-plate c, which is bent over to form an outwardly-extending spring arm, D, and beneath the outer or free end of the latter is an inclined rib or projection, c', herein 60 shown as being struck up from the plate c, the inclination of said rib being indicated by the dotted lines in Fig. 1. The supporting-plate A has on its under side an inclosed guiding-passage, E, for the strip of lace or other material which is to be attached to the edge of the fabric by the stitches which secure the hem, said guiding-passage being forward of the rear end of the hemmer, and below and mainly on the inner or right-hand side of the latter, 70 Fig. 1, with its outer edge directly beneath or in line with said hemmer. The guiding-passage, as herein shown, is formed by a downwardly and inwardly turned lip, a, on the plate A, and an adjustable hollow guide-piece, F, 75 formed of thin metal, and having spring-arms f, passing through slots a' in a rib, a', on the under side of the plate A. The guide-piece F may be adjusted toward or from the lip a, to vary the width of the guiding-passage E, the 80 spring-arms f having sufficient friction in the slots a' of the rib a' to hold said guide-piece in any position to which it may be adjusted. The bottom of the presser-foot B is preferably recessed slightly at b' on its inner side, beneath 85 which the hem and the secured strip passes, so as to compensate for the increased thickness of the work at this side, and thus insure the accurate working of the feed.

In the use of my device the fabric to be 90 hemmed passes beneath the spring-arm or friction-spring D, the latter pressing the fabric gently against the inclined rib c', which has a tendency to deflect the fabric toward the hemmer C, which latter turns the edge to form 95 a hem in the usual manner. The strip of lace or other material to be attached to the edge of the fabric simultaneously with the sewing of the hem passes through the guiding-passage E, and as the inner edge of the latter is in line 100

with the hemmer, the accurate presentation of the strip to the sewing mechanism, together with the turned hem, is thus secured.

I claim as my invention—

- 5 1. In a sewing-machine attachment, the combination, with a hemmer, of a supporting-plate, to the upper side of which said hemmer is attached, said supporting-plate having on its under side, below the hemmer and forward of the rear end thereof, an inclosed strip-guiding passage, which is mainly inside or to the right of said hemmer, but having its outer edge in line with the latter, substantially as set forth.
- 10 2. In a sewing-machine attachment, the combination, with a supporting-plate having a strip-guiding passage on its under side, of a hemmer supported above said plate, a friction-spring in front of said hemmer, and an inclined rib or projection beneath the outer end 20 of said friction-spring, substantially as set forth.

3. The combination, with the hemmer, of the supporting-plate having the lip *a* and slotted rib *a'*, of the adjustable guide-piece F, said lip and guide-piece serving to form an adjustable or variable strip-guiding passage, substantially as set forth. 25

4. In a sewing-machine attachment, the combination, with a hemmer, of a supporting-plate therefor, having on its under side, below the hemmer and forward of the rear end thereof, an inclosed strip-guiding passage, mainly inside or to the right of said hemmer, and a presser-foot having a recess, as *b*, on the inner side of its lower or bearing surface, substantially as set forth. 30 35

In testimony whereof I affix my signature in presence of two witnesses.

WILLIAM R. CLARK.
